SIGN.

William W. Hays, Greenville, Tex., assignor of twenty per cent to Arthur W. Lilly, Greenville, Tex.

Application December 10, 1937, Serial No. 179,039

13 Claims. (Cl. 40—133)

This invention relates to new and useful improvements in signs.

One object of the invention is to provide an improved illuminated sign which effectively simulates a neon tube sign and which is economically applicable to signs of small and medium sizes.

10 An important object of the invention is to provide an improved sign wherein a tube-like illumination, which gives the appearance of a neon tube and which conforms to the shape of the letter, is provided and also wherein a reflected glow, simulating the glow of a neon tube, surrounds said indicia, whereby a most attractive 15 and inexpensive sign, which may be of a relatively small size for window display purposes, is produced.

Another object of the invention is to provide a sign having relatively narrow slots or openings 20 conforming to the shape of the indicia therein, with means for directing a colored light through said openings so that the illumination visible through the openings produces the appearance of a tube; there being additional light openings 25 surrounding the indicia and means for reflecting the light rays passing through these openings onto the background surrounding the indicia, whereby a reflected glow is produced around the indicia.

30 A construction designed to carry out the invention will be hereinafter described, together with other features of the invention.

The invention will be more readily understood from a reading of the following specification and 35 by reference to the accompanying drawing, in which an example of the invention is shown, and wherein:

Figure 1 is a front elevation of a sign, constructed in accordance with the invention.

40 Figure 2 is a transverse, vertical, sectional view, taken on the line 2—2 of Figure 1.

Figure 3 is a horizontal, cross-sectional view, taken on the line 3—3 of Figure 1.

45 Figure 4 is a rear elevation of the background on which the indicia is displayed.

Figure 5 is an enlarged, front elevation of a portion of the indicia, showing the reflected glow surrounding the indicia, and

50 Figure 6 is a reduced front elevation of a slightly modified form of the invention.

In the drawing, the numeral 10 designates a light reflecting casing or housing which has its front 11 open. A suitable electrical receptacle or socket 12 is mounted in the bottom of the 55 housing and electrical current is conducted there-

to by electrical lead wires 13 which pass through an opening in the rear wall of the casing. An incandescent lamp or bulb 14 is screwed into the receptacle and illuminates the interior of the casing. It is noted that the particular construction of the casing is subject to variation, as any suitable light reflecting casing may be employed.

The open front 11 of the casing is closed by a background panel 15 which extends completely thereacross and which has a general rectangular 10 shape. However, the shape of the casing controls the shape of the panel and therefore, said panel may be of any desired shape. The panel is suitably secured to an outwardly directed, peripheral flange 16 which is provided on the casing. 15 Indicia 17 are painted, or otherwise displayed on the outer face of the panel 15, whereby it is clearly visible to an observer viewing the sign. These indicia have been shown in the form of letters but manifestly, they could be figures, pictorial illustrations, or other displays.

20 The background panel is provided with a plurality of relatively narrow slots or openings 18, one or more of which is provided for each letter. The opening for each letter conforms to the shape 25 of that letter and is preferably disposed centrally thereof. Since each opening or slot 18 extends entirely through the panel, the light rays from the interior of the housing are visible 30 through said openings, whereby a narrow illuminated slot, conforming to the shape of the letter, is visible to the observer. These illuminated slots or openings simulate and give the appearance of 35 illuminated tubes, such as neon tubes.

It is preferable to color the light rays prior 35 to their passage through the openings 18 and for this purpose, a colored sheet 19 of transparent material, such as Cellophane, or colored or coated glass, is secured to the rear face of the panel 15 and covers the openings in said panel. A suitable transparent reinforcing cloth sheet 19 may overlie the colored sheet and serves to prevent displacement of the same, as well as to prevent buckling or wrinkling of said sheet, due to heat from the light bulb 14. The 40 sheet 19 may be of a desired color and thus, a colored light of the shape of the openings 18 is visible. Manifestly, the colored sheet could be eliminated and colored transparent strips for covering the individual openings, substituted 45 therefore, or if desired, the interior walls of the casing or the bulb 14 could be colored, in which case, the colored sheet or strips could be omitted.

50 From the foregoing, it will be manifest that the indicia are clearly set out in illuminated 55

openings, which openings, being relatively narrow, simulate illuminated tubes. As is well known, neon tubes produce a reflected glow which surrounds the tube and in order to produce this glow so that the sign herein gives substantially the complete effects of a neon tube, additional slots or openings 21 are formed in the panel 15. As is clearly shown in Figures 1 and 4, these openings 21 extend completely around the indicia on the panel and are spaced from said indicia. The openings may be covered with the colored sheet 18 or the rays passing through the openings may be otherwise suitably colored. A border or reflecting member 22 is secured to the peripheral portion of the panel, being spaced from said panel by a frame 23, which is interposed between the border and panel. The border overlies the panel in spaced relation thereto, and is provided with a central aperture or opening 24 through which the indicia 16 is visible. The aperture preferably conforms to the top, bottom and ends of the indicia (Figure 1) and the inside edge of the aperture is sufficiently close to the indicia to cover or overlie the openings 21 which extend around said indicia. With such arrangement, the openings 21 are not visible to an observer as the inner edge portion of the border or reflecting members overlies said openings, being spaced therefrom by the frame 23. The openings 17 which form the indicia are, of course, clearly visible.

When the sign is illuminated, the illuminated, colored openings 17 clearly set out the indicia and give the appearance of an illuminated tube. The light passing from the interior of the housing also passes through the openings 21 and strikes the rear face of the overlying border 22, from which it is reflected onto the background panel 15 around the indicia, whereby said indicia is surrounded by a reflected brilliant glow (Figure 5). This glow simulates the glow of the usual neon tube and together with the tubular appearance of the illuminated slots or openings 17 produces a sign which gives substantially the same effect as a neon tube sign. It is not essential that the border 22 have its inner edge of its aperture 24 conforming to the general outline of the letters and said aperture could be substantially rectangular in shape, as shown in Figure 6. Such shape of the aperture has been found to produce a satisfactory glow around the indicia. It is also pointed out that although the indicia 16 have been described as first being painted, or displayed on the panel 15, after which the slots 17 are formed therein, the painting or displaying may be dispensed with entirely with the slots or openings 17 forming the indicia or letters.

The sign simulates closely the effects of a neon tube sign and is most economical in manufacture. The sign may be made of any desired size and is ideal for window and counter display. Its upkeep, or cost of operation is small due to the fact that one bulb or lamp is sufficient to illuminate the same. The panel 15 and casing, as well as the reflecting member 22, may be constructed of heavy pasteboard, cardboard, metal, wood or other suitable material. It is noted that if desired, the rear face of the reflecting member 22 may be colored to intensify the color of the glow.

What I claim and desire to secure by Letters Patent is:

1. A sign including, a panel having relatively narrow openings therein which openings simulate tubes and are shaped to form indicia, means

for directing light rays through said openings to illuminate the same to produce an illuminated tube effect, the panel having additional openings surrounding the narrow openings, and means overlying such additional openings for intercepting the light rays passing therethrough and for reflecting said rays onto the panel around the narrow openings, whereby a reflected glow around the simulated tubes is produced. 5

2. A sign including, a panel having relatively narrow openings therein which openings simulate tubes and are shaped to form indicia, means for directing light rays through said openings to illuminate the same to produce an illuminated tube effect, means for reflecting additional light rays onto the panel around the openings for setting up a glow around the openings, whereby said glow appears to be reflected from the simulated tubes, and means for coloring the light rays passing through the openings and also for coloring the reflected glow. 10

3. A sign including a panel having relatively narrow openings therein which openings simulate tubes and are shaped to form indicia, means for directing light rays through said openings to illuminate the same to produce an illuminated tube effect, the panel having additional openings surrounding the narrow openings, means overlying such additional openings for intercepting the light rays passing therethrough and for reflecting said rays onto the panel around the narrow openings, whereby a reflected glow around the simulated tubes is produced, and means interposed between the source of light and the openings for coloring the light rays passing through said openings. 25

4. An illuminated sign simulating a neon sign including, a display panel having indicia displayed thereon and having relatively narrow slots therein, said slots conforming to the indicia on said panel, means for directing light rays through said slots whereby the illuminated slots simulate tubes, said panel having openings surrounding the indicia whereby light rays may pass therethrough, and means spaced from the face of the panel and overlying said openings whereby the light rays passing therethrough are reflected onto the panel around the indicia and simulated tubes to produce a glow. 40

5. An illuminated sign simulating a neon sign including, a display panel having indicia displayed thereon and having relatively narrow slots therein, said slots conforming to the indicia on said panel, means for directing light rays through said slots whereby the illuminated slots simulate tubes, said panel having openings surrounding the indicia whereby light rays may pass therethrough, means spaced from the face of the panel and overlying said openings whereby the light rays passing therethrough are reflected onto the panel around the indicia and simulated tubes to produce a glow, and means for coloring the light rays passing through said slots and openings. 50

6. An illuminated sign simulating a neon sign including, a display panel having indicia displayed thereon and having relatively narrow slots therein, said slots conforming to the indicia on said panel, means for directing light rays through said slots whereby the illuminated slots simulate tubes, said panel having openings surrounding the indicia whereby light rays may pass therethrough, means spaced from the face of the panel and overlying said openings whereby the light rays passing therethrough are reflected onto the panel around the indicia and simulated tubes 60

to produce a glow, and a coloring medium secured to the panel for coloring the light rays passing through the slots and openings.

7. An illuminated sign simulating a neon sign including, a light reflecting housing having its front open, means within the housing for illuminating the same, a display panel closing the open front of the housing and having relatively narrow slots therein which slots are shaped to form indicia, the slots permitting light rays to pass therethrough whereby the illuminated slots simulate tubes, the panel also having openings therein which are disposed around the slots, and means for reflecting the light rays passing through the openings onto the panel to form a reflected glow around the simulated tubes.

8. An illuminated sign simulating a neon sign including, a light reflecting housing having its front open, means within the housing for illuminating the same, a display panel closing the open front of the housing and having relatively narrow slots therein which slots are shaped to form indicia, the slots permitting light rays to pass therethrough whereby the illuminated slots simulate tubes, the panel also having openings therein which are disposed around the slots, means for reflecting the light rays passing through the openings onto the panel to form a reflected glow around the simulated tubes, and a coloring medium secured to the panel for coloring the light rays passing through the slots and openings.

9. An illuminated sign simulating a neon sign including, a light reflecting housing having its front open, means within the housing for illuminating the same, a display panel closing the open front of the housing and having relatively narrow slots therein which slots are shaped to form indicia, the slots permitting light rays to pass therethrough whereby the illuminated slots simulate tubes, the panel also having openings therein which are disposed around the slots, a border secured to the outer surface of the panel and spaced therefrom and having an aperture through which the illuminated slots are visible, said border overlying the openings to reflect the light rays passing through the openings onto the panel to form a reflected glow around the simulated tubes, and a transparent colored sheet secured to the panel

for coloring the light rays passing through the slots and openings.

10. A sign including, a panel having narrow light admitting openings therein to permit light to pass therethrough, said openings simulating tubes and forming indicia displayed on the panel, and means for passing additional light rays through the panel and for reflecting these latter rays onto the outer surface of the panel for setting up a glow around the openings, whereby said openings simulate tubes and the glow appears to be reflected from said simulated tubes.

11. A sign including, a panel having relatively narrow light emitting portions therein to permit light to pass therethrough, said portions being so disposed in the panel as to generally follow a shape representative of indicia, additional light emitting portions in the panel, and means overlying and spaced from said additional light emitting portions, said additional light emitting portions and the means overlying the same being disposed with relation to the light emitting portions in the panel so as to reflect light rays onto the surface of said panel.

12. A sign including, a panel having light emitting portions therein which portions are shaped to form indicia means for directing light rays through said light emitting portions to illuminate the same, the panel having additional light emitting portions which encircle the indicia, and means overlying such additional light emitting portions for intercepting the light rays passing therethrough and for reflecting the same onto the panel around the first named light emitting portions which form indicia to set up a reflected glow around such indicia.

13. A sign including, a panel having light emitting portions therein which portions are shaped to form indicia and are of such size as to simulate a gaseous tube, means for directing light rays through said light emitting portions so as to illuminate the same, additional light emitting portions adjacent the light emitting portions of the panel, and means overlying such additional light emitting portions for reflecting the light rays passing through these latter portions back onto the surface of the panel.

WILLIAM W. HAYS.
